UNITED STATES PATENT OFFICE.

WILLIAM J. HOFFMANN, OF NEW YORK, N. Y.

FIGURE WHEELED TOY.

Application filed May 4, 1921. Serial No. 466,675.

To all whom it may concern:

Be it known that I, WILLIAM J. HOFFMANN, a declarant for citizenship in the United States, at present a citizen of Germany, and a resident of the city, county, and State of New York, have invented certain new and useful Improvements in Figure Wheeled Toys, of which the following is a specification.

10 This invention relates to improvements in toys and has for its principal object to provide a device which is primarily designed to amuse.

Another object of the invention resides in 15 the provision of a toy having mounted thereon a movable object which will attract and hold the attention of children and others and which is designed to represent a dancing figure.

20 A further object of the invention is to provide a novel means for intermittently oppositely rotating an object when the drive wheels of the toy are rotated by traction upon a surface.

25 With these and other objects in view the invention consists in the novel construction, combination and arrangement of parts which will be fully set forth in the following specification and illustrated in the accompanying drawings, in which:

Figure 1 is a side view in elevation of this toy.

Figure 2 is a top plan view of Figure 1.

30 Figure 3 is a rear plan and partial sectional view through the device.

Figure 4 is a fragmentary detail view of the drive axle.

Referring to the drawing by characters of reference the numeral 10 designates a 40 platform provided with downturned legs 11 intermediate the ends of the side edges thereof.

Formed at one end of the platform is a downwardly and outwardly extending 45 tongue 12 provided at its lower edge with a roll 13. A struck-up portion forming an eye 14 is formed in the tongue near its upper end through which a flexible member 15 is adapted to be secured.

50 Formed near the lower ends of the legs 11 are alined openings in which the drive axle 16 is rotatably mounted. At each end of the axle is a flattened portion 17 which is passed through a slot formed in the hub 55 of a stamped sheet metal wheel 18.

As shown in Figure 3 the outer ends of the flattened portions are spread, as at 19, to secure the wheels 18 in place. Struck at spaced intervals intermediate the ends of the axle and spaced equidistant from the longitudinal center thereof are ears 20 around which are cast the cam wheels 21 the same being provided with inwardly extending cams 22 which are arranged at diametrically opposite points so that as the shaft rotates they will alternately engage the friction wheel to be more fully herein-after described.

Formed centrally of the platform 10 is an opening through which a vertical spindle 70 23 extends. Mounted on the upper end of the spindle 23 is a figure 24 which may be stamped from sheet metal, card board or other desirable material.

A base member 25 is secured to the spindle 75 in such manner as to rest on the platform immediately adjacent the central opening. A friction wheel 26 is secured to the lower end of the spindle 23 in such position as to be disposed between the upper edges of the 80 cam wheels so that the cams 22 will alternately engage the periphery of the wheel and cause the same and its associated mechanism to rotate.

In order to hold the wheel in proper position a substantially U shaped bracket 27 is provided having its upper elements formed with ears 28 which are extended through slots in the platform 10, formed at opposite sides of and equidistant from the central 90 opening therein.

The bight portion of the U shaped member is formed with a central opening for the reception of the lower end of the spindle 23 to hold it in a vertical position. A collar 95 29 is fixed on the spindle 23 between the wheel 26 and the bight portion of the U shaped bracket, to properly space the wheel from the bracket and provide a thrust bearing which will prevent longitudinal displacement of the spindle.

In use it will be seen that as the flexible member 15 is pulled, the device will be drawn over a surface, thus causing the wheels 18 to rotate so that the cams 22 will 105 alternately engage the friction wheel 26, causing the same and associated parts to revolve so that the figure 24 will turn first in one direction and then the other. It is to be understood that if so desired a skirt 110

30 of some light material may be secured to the figure in order to render the device more attractive in appearance.

While in the foregoing there has been 5 shown and described the preferred form of this invention it is to be understood that minor changes in the details of construction, combination and arrangement of parts may be resorted to without departing from the 10 spirit and scope of the invention.

Having thus described my invention, what I claim as new and desire to secure by Letters Patent, is:—

1. A toy comprising a sheet metal plate 15 having downturned side members and an end member adapted to drag upon a surface, an axle rotatable in said down turned members, wheels fixed at the ends of said axle, a rotatable spindle mounted in a vertical 20 plane in said plate, a figure carried by said spindle, a cylindrical friction element on the spindle, and means carried by said axle to make alternate contact with said element whereby said figure is periodically rotated 25 in opposite directions.

2. A toy comprising a movable figure, an axial standard therefor, a platform supporting said standard, wheels on which said platform is mounted, cams actuated by the 30 rotation of said wheels, said cams being spaced and arranged in opposed relation,

and a pliable disc fixed on said stand and adapted to contact with the faces of said cams alternately whereby a smooth change of direction of rotation is imparted to said 35 figure.

3. A toy comprising a platform, wheels supporting said platform, an axle revoluble upon the rotation of said wheels, cams on said axle, a vertical spindle extending 40 through the platform, a figure at the upper end of the spindle, and a friction wheel at the lower end of the spindle in such position as to be alternately engaged by the cams whereby the wheel and its associated parts 45 will be intermittently revolved in opposite directions.

4. A toy comprising a platform, a tongue integral therewith extending outward and downward as a support, an axle housed in 50 said platform, wheels rigid on the ends of said axle, a pair of side cams secured in opposed relation on said axle, a vertical spindle rotatably mounted on said platform directly over the axle, a friction wheel fixed on the lower end of said spindle, said wheel being alternately engaged by said cams, and a manikin mounted on said spindle.

In testimony whereof I have signed my name to this specification.

WILLIAM J. HOFFMANN.
